UNITED STATES PATENT OFFICE

104,507

DESIGN FOR A BICYCLE MUDGUARD

Ewald F. Pawsat, Maysville, Ky., assignor to Wald Manufacturing Company, Incorporated, a corporation of Kentucky

Application January 18, 1937, Serial No. 67,121

Term of patent 14 years

To all whom it may concern:

Be it known that I, Ewald F. Pawsat, a citizen of the United States, residing at Maysville, in the county of Mason and State of Kentucky, have invented a new, original, and ornamental Design for Bicycle Mudguards, of which the following is a specification, reference being had to the accompanying drawing, forming a part thereof.

In the drawing:

Figure 1 is a side view of a bicycle mudguard showing my new design.

Figure 2 is an end elevation of said mudguard.

Figure 3 is a transverse section of said mudguard.

I claim:

The ornamental design for a bicycle mudguard, as shown.

EWALD F. PAWSAT.
